US00D716966S

(12) **United States Design Patent**
Lizari Illarramendi

(10) **Patent No.:** **US D716,966 S**
(45) **Date of Patent:** **** Nov. 4, 2014**

(54) **MEDICAL AND LABORATORY EQUIPMENT**

(71) Applicant: **Borja Lizari Illarramendi**, Burgos (ES)

(72) Inventor: **Borja Lizari Illarramendi**, Burgos (ES)

(73) Assignee: **Kiro Robotics, S.L.**, Gipuzkoa (ES)

(**) Term: **14 Years**

(21) Appl. No.: **29/443,369**

(22) Filed: **Jan. 16, 2013**

(30) **Foreign Application Priority Data**

Jul. 31, 2012 (EM) 001338156-0001

(57) **CLAIM**

The ornamental design for a medical and laboratory equipment, as shown and described.

DESCRIPTION

FIG. 1 is a perspective view of a medical and laboratory equipment illustrating my new design showing equipment on an internal platform;

FIG. 2 is a front plan view of FIG. 1;

FIG. 3 is a rear view of FIG. 1;

FIG. 4 is a right-side view of FIG. 1;

FIG. 5 is a left-side view of FIG. 1;

FIG. 6 is a perspective view of a medical and laboratory equipment of a second variant showing the internal platform for equipment;

FIG. 7 is a front plan view of FIG. 6;

FIG. 8 is a rear view of FIG. 6;

FIG. 9 is a right-side view of FIG. 6; and,

FIG. 10 is a left-side view of FIG. 6.

The broken lines shown in the Figures illustrate the environment only and form no part of the claimed design.

1 Claim, 10 Drawing Sheets
